(57) **CLAIM**

I claim the ornamental design for a cleaning robot, as shown and described.

DESCRIPTION

1.1 is a front view of a first embodiment of a cleaning robot;
1.2 is a back view of the first embodiment;
1.3 is a left view of the first embodiment;
1.4 is a right view of the first embodiment;
1.5 is a top view of the first embodiment;
1.6 is a bottom view of the first embodiment;
1.7 is a front, top perspective view of the first embodiment;
1.8 is a back, bottom perspective view of the first embodiment;
2.1 is a front view of a second embodiment of a cleaning robot;
2.2 is a back view of the second embodiment;
2.3 is a left view of the second embodiment;
2.4 is a right view of the second embodiment;
2.5 is a top view of the second embodiment;
2.6 is a bottom view of the second embodiment;
2.7 is a front, top perspective view of the second embodiment; and

(Continued)

2.8 is a back, bottom perspective view of the second embodiment.
